MERCURY SWITCH TESTER

Calvin F. Brown, Silver Spring, Md., assignor to
the United States of America as represented by
the Secretary of the Navy

Application July 8, 1947, Serial No. 759,630

5 Claims. (Cl. 175—183)

1 This invention relates to a method of testing mercury switches and an appliance therefor. The appliance includes a power operated rotor to simulate a spinning projectile in flight, whereby the mercury is displaced from a contact chamber of the closed switch through a permeable partition to a separate sump to open the switch. In switches of the type adapted to be tested by the mercury switch tester of the invention, a globule of mercury is contained in an interior contact chamber and acts as a fluent conductor between two spaced contacts to maintain the switch in normally closed condition. The switch to be tested forms no part of this invention.

The rotor, or rotary carrier, is provided with means for initially holding the closed switch axially therein until said rotary carrier has attained a desired speed, when the switch is forced centrifugally to an off-center or eccentric position, and the mercury drained by centrifugal force from the contact chamber to the sump.

The method of testing consists in timing opening of the switch which results from the passage of the mercury from the contact chamber through a permeable partition into the sump, so that switches may be determined to operate within a known time under a standard centrifugal force.

In order better to describe the present invention, reference is made to the accompanying specifications and drawings in which:

Fig. 1 is an enlarged vertical sectional detailed view of a switch testing device embodying the invention showing a mercury switch centered in an initial position on the axis of rotation of the rotor, or rotary carrier, and clamped by a depressed abutment under pressure of an axially aligned hand tool;

Fig. 2 is an exterior elevational view of the switch tester on a reduced scale;

Fig. 3 is a fragmentary sectional view similar to Fig. 1 showing the switch unit to be tested in testing position.

Fig. 4 is a schematic plan view showing an electrical circuit employed with the testing appliance of the invention.

Referring to the drawings it is seen that the rotor, as a unit, is mounted upon an upright spindle or rotary shaft 10 which is driven from a suitable source, and carries the mercury switch to be tested as shown at 11. The switch is clamped or clasped in a channel or groove 39 in a circular head 12 of the rotary unit, the said channel being insulated as at 13; and the head in its upper face being recessed, to receive and 55

2 contain a fixed, concentric conductor ring 14 which is insulated from the head by an insulating assembly 16. The vertical position of the axis shaft 10 assures a centrifugal force unmixed with gravitational or other forces. The rate of rotation of the shaft governs the centrifugal force, and this rate of rotation may be obtained from a suitable tachometer (not shown) attached to the shaft.

10 10 A holder for the switch includes a radially arranged, spring biased plunger or clamp pin 17 mounted for sliding movement in a sleeve 37 carried in the circular head 12. Thus the switch is held firmly between the end of the pin 17 and a movable jaw or abutment 18.

The abutment 18 is fashioned as an integral jaw projecting downwardly from an upright tubular depressible sleeve 19 which terminates at its upper end in a head 20 having an exterior central cavity or seat 21 for a portable hand tool 22. The sleeve 19 is reciprocable in an open-end upright cylindrical guide 23, here shown as hinged at 24 on the top of the circular head 12. A spring 26, anchored at its ends to the depressible sleeve and the stationary guide, respectively, tends to lift or retract the jaw 18 from the position in which it engages one end of the switch 11. The longitudinal movement of this tubular plunger is guided by co-action of a guide lug or screw 27 on the plunger with a complementary groove 28 on the hinged holder.

For holding down the switch during the time test, a conventional latch assembly, shown generally at 29, may be carried by the shoulder 30 of the guide 23 and adapted to engage a latch stop 31 in the head 12.

A spring biased detent 35 carried by the head 12 is adapted to engage an indentation 36 in pin 17 to restrain the pin in its retracted position 40 while the switch is inserted in the head 12 and the abutment 18 lowered into place.

In carrying out the test, the guide sleeve 23 is first swung on its hinge 24, and the switch 11 is inserted by hand in the recessed head 12 with its base end against the spring-thrust pin 17. The guide sleeve 23 is then restored to upright position, the hand tool 22 is applied to the cavity 21 and then by pressure on the tool the tubular plunger is depressed so that the abutment 18 engages the other end of the switch. The switch is now rigidly held axially within the head 12 as in Fig. 1.

The rotary shaft or spindle is now driven to spin the head 12 and its contained switch. Upon attainment of the desired rotational velocity, the

pressure on the hand tool 22 is released, the abutment 18 automatically lifted from engagement with the switch, and the spring biased pin 17 and centrifugal force projects the switch to the eccentric position of Fig. 3 and in contact with the ring 14. Due to the continued rotation of the head 12 with the switch in eccentric position, centrifugal force of the spinning head causes the flow of the mercury that opens the switch. The time required for the switch contacts to open may be determined by a suitable electric time clock 42. One terminal of the clock is adapted to be connected to a suitable source of operating voltage (not shown) and the other terminal is shown connected to the head 12 of the testing unit through a suitable sliding contact 43. Another sliding contact 44 carried by the holder 32 contacts the conductor ring 14, to complete a circuit through the switch contacts simultaneously with the displacement of switch 11 by centrifugal force together with the action of the spring biased plunger 17. This circuit may be traced as follows: from the sliding contact 43, through the head 12, the sleeve 37, the plunger 17, to one switch terminal; from the other switch terminal to the conductor ring 14, sliding contact 44, through the time clock and voltage supply source back to sliding contact 43. Obviously the circuit may be modified by providing, for example, a common ground for the potential source and switch terminal.

After the test, the switch 11 is turned end-for-end and replaced in eccentric position; the rotary carrier is then revolved and by centrifugal force the mercury is returned from the sump to the conducting chamber, to close the switch and restore it to its initial normal condition.

I claim:

1. A centrifugal testing appliance comprising a rotor, a work holder mounted thereon, said holder including a spring pressed plunger and a movable abutment coacting therewith for initially holding on the rotor axis a unit to be tested, means for moving the abutment out of engagement with said unit to permit displacement of the unit from the axis to a position for testing, and a stop positioned to coact with the plunger for retaining the unit in displaced position whereby the unit is subjected to centrifugal force testing.

2. A centrifugal testing appliance for subjecting a unit to be tested to centrifugal force and simultaneously to an electric current, comprising a rotor, a work holder mounted thereon, said work holder including a spring pressed plunger and a movable abutment coacting therewith for holding on the rotor axis a unit to be tested, means for moving the abutment out of engagement with the unit to permit displacement of said unit from the axis, a stop positioned to coact with the plunger for retaining the unit in displaced off axis position whereby the unit is subjected to centrifugal force, said plunger and said stop being

so insulated as to form branches of an electrical circuit to be bridged by the unit, and an electrically operated time clock in electrical circuit with said unit and said branches and operable for indicating the time required to cause the unit to function under centrifugal force.

3. An appliance for determining the time necessary to break the circuit through a mercury switch under test in response to a predetermined centrifugal force comprising a rotor mounted for rotation about a vertical axis, a work holder mounted on said rotor for mounting a mercury switch in a plane normal to said axis, said work holder including means for initially retaining said switch on the axis, a spring pressed plunger for urging the switch away from the axis along said plane, a ring for retaining the switch at a fixed distance from the axis whereby a predetermined centrifugal force acts thereon, said retaining means including an electrical contact element and a spring pressed plunger, means insulating the contact element from the holder and plunger, electrical circuit means for supplying current to the element and plunger respectively and through said switch and timing means in said circuit with the contact and operable to indicate the time necessary for the switch to break the circuit under a known centrifugal force.

4. A centrifugal switch testing appliance comprising means for rotating at a substantially fixed rate a switch to be tested, a spring pressed plunger and spring pressed abutment elements for retaining said switch on the axis of rotation, means for releasing the abutment for spring actuated movement out of retaining position whereby the spring action of the plunger may force the unit away from said axis, means for passing an electrical current through the unit in displaced off-axis position, and means for measuring the time period of flow of current.

5. A centrifugal testing appliance for subjecting a unit to be tested to a predetermined centrifugal force, comprising a rotor adapted for rotation at a measured rate, timing means connected in series with a unit to be tested and a source of electric current, means for initially holding on the axis of said rotor the unit to be tested, and means for displacing the unit a predetermined distance from the axis, upon the attainment of the desired rotational velocity by the rotor, whereby the unit is subjected to said predetermined centrifugal force, said timing means indicating the time required to cause the unit to function in this latter position.
